15 Claims. (Cl. 179—27.54)

1

The present invention relates in general to switching mechanisms and in particular to switches of the cross-bar type such as are employed to effect connections in automatic telephone systems.

It is an object of the invention to provide an improved cross-bar switch which is adapted to be operated in a step-by-step manner so as to reduce the amount of auxiliary control equipment required.

It is a further object of the invention to provide an improved cross-bar switch wherein a single group of magnets serves to selectively control both rank and file selecting members.

Still another object of the invention is to provide an improved cross-bar switch wherein an actuated contact set is mechanically latched under the control of a common release magnet.

Cross-bar switches have heretofore been disclosed wherein a number of contact sets are disposed in intersecting rows and wherein two intersecting groups of selecting members are arranged so that the actuation of one member in each group causes the operation of a contact set at the point of intersection of the two actuated members. Individual magnets have generally been provided for actuating each of the selecting members, although in some instances the selecting members of a group have been actuated in a step-by-step manner by a ratchet mechanism common to the group. Cross-bar switches using individual magnets for actuating each selecting member have also been proposed wherein the operated contact set is mechanically latched so as to permit restoration of the selecting members and associated magnets, and in which the operated contact set is released by the reoperation of one or both of the members used to operate said contact set.

The principal features of the present invention are the provision of an improved cross-bar switch having individual magnets for actuating each member of one group of selecting members wherein the members of another group of selecting members intersecting the first group are selectively actuated by the joint operation of one of said selecting magnets and a common control magnet, wherein the actuated selecting member of said other group is maintained actuated by said control magnet when the selecting magnet restores, wherein the subsequent operation of one of said selecting magnets causes the operation of a contact set at the intersection of the two actuated selecting members, wherein said contact set is mechanically latched when the select-

2

ing and control magnets restore, wherein subsequent operations of any of the selecting magnets will not disturb the connection established by said one contact set and wherein said one contact set is released by the operation of a common release magnet.

Other features of the invention will appear upon a further perusal of the specification taken in conjunction with the accompanying drawings comprising Figs. 1 to 10, in which:

Fig. 1 is a perspective skeleton view of a portion of a switching mechanism constructed in accordance with the invention;

Fig. 2 is another perspective showing the method of mounting one of the contact sets and an operating member therefor;

Figs. 3, 4, 5 and 6 illustrate various steps in the operation of the switching mechanism of Fig. 1;

Fig. 7 is a top view of the switching mechanism of Fig. 1 including the supporting frame and other details of construction;

Fig. 8 is a front view as seen from the bottom of Fig. 7;

Fig. 9 is a rear view as seen from the top of Fig. 7; and

Fig. 10 is a side view as seen from the right of Fig. 7.

The invention will first be briefly described, after which a detailed description of the illustrated embodiment thereof will be given. A plurality of contact sets are disposed in intersecting rows and two intersecting groups of selecting members are provided for selectively operating any of the contact sets through operating members individual thereto. Each selecting member of one group is arranged to move a row of the operating members so that any one of the operating members so moved may be engaged by corresponding ones of the selecting members in the second group to operate the contact set at the intersection of the two actuated selecting members. Individual magnets are provided for actuating each selecting member in the second group. The drawing illustrates two of the ten selecting magnets. A common control magnet is provided for operating the selecting members in the first group. This control magnet is normally ineffective to operate any of the members associated therewith unless one of the selecting magnets is operated, in which case a corresponding finger is moved by the operated selecting magnet so that the control magnet is effective to actuate a selecting member in the first group which corresponds to the operated selecting mag-

net. These fingers are arranged so that the control magnet is effective to hold the actuated selecting member in the first group after the selecting magnet is released. Thus by first operating a selecting magnet, next operating the control magnet, and then releasing the selecting magnet; the selecting member in the first group corresponding to the operated selecting magnet will be actuated and held by the control magnet. The actuated selecting member moves its associated row of operating members so that a subsequent operation of any of the selecting magnets will operate the contact set located at the intersection of the selecting member in the first group held by the control magnet and the selecting member in the second group actuated by the subsequently operated selecting magnet. A latching mechanism is provided which is operated in response to the restoration of the control magnet to hold the actuated selecting member in the second group when the selecting magnet associated therewith is subsequently released. The operated contact set is thus held independently of the selecting and control magnets. A common release magnet is provided for releasing the latching mechanism to permit restoration of the switching mechanism to normal.

Referring now to Fig. 1, portions of two of the selecting magnets, 1 and 2, are shown. Each of these magnets comprises a bar of magnetic material of rectangular cross-section with a winding on the central portion of the bar. These magnets are provided with magnetic armatures, such as 37 and 44, which are bars of L-shaped cross-section having a portion cut out of the center thereof to clear the magnet winding. Each of these armatures has a pair of arms, such as 4 and 5, extending from one end thereof. Each armature has a further arm, such as 6, welded thereto at a predetermined distance from one end thereof, which distance is different for each armature. These latter arms engage slots in corresponding selecting members, such as 38, 38' and 38'', hereinafter termed file selecting members. The arms 5 each engage a contact spring set, such as 3, not shown in Fig. 1 but which may be seen in Figs. 7 and 8. Each of the magnet armatures is pivoted so as to permit rotation thereof about an axis parallel to the length of the associated magnet. The pivot points are located near the corner of the L-shaped cross-section at either end of the armature. Thus when magnet 2 is energized, the armature 37 is rotated in a counter-clockwise direction causing the selecting member 38 to move towards the lower right corner of the drawing. These file selecting members are biassed towards the upper left corner of the drawing by flat springs, such as 9, engaging slots, such as 10, in the ends thereof. These springs are not shown in Fig. 1 but may be seen in Figs. 7 and 9. The biassing of the file selecting members in turn biasses the armatures, such as 37, in a clockwise direction against stops, such as 11, shown in Figs. 7 to 9.

Two further selecting members, such as 41, hereinafter termed rank selecting members, are shown intersecting the file selecting members. Each of these rank selecting members is pivoted so as to permit rotation thereof about an axis perpendicular to and intersecting the file selecting members. Arms, such as 40, extend from one end of each of these rank selecting members. A control member 14, common to all of the rank selecting members, is located just above the arms

such as 40 and 5. A number of resilient fingers, such as 15, are welded at one end to the control member 14. The free ends of these fingers are positioned so as to be operatively moved by the arms, such as 4, extending from the armatures of the selecting magnets. When so moved the lowermost portion 39 of the free end of the finger 15 is in position to engage the arm, such as 40, extending from the corresponding rank selecting member so as to rotate said member in a clockwise direction when the control member 14 is moved towards the lower right part of the drawing by the operation of a control magnet 16, which is provided with an armature 17 engaging a slot 18 at the end of the control member. A coil spring 19 biasses the armature 17 and control member 14 towards the upper left part of the drawing. Each of the rank selecting members is biassed in a counter-clockwise direction against a stop, such as 57, by a coil spring, such as 49; which stops and springs are shown in Fig. 9. Each of the rank selecting members has a number of arms, such as 21, extending therefrom; each of these arms being located immediately above a corresponding one of the file selecting members. These arms each support a contact operating member, such as 43, made of electrical insulating material. The operating members are each provided with two slots by means of which they are suspended on hooks projecting from a frame member as illustrated in Fig. 2. These operating members are not engaged by the file selecting members when the rank selecting members are in their normal positions, but when a rank selecting member is rotated, as previously described, the operating members associated therewith drop until their lower edges are engaged in slots in the file selecting members located thereunder. With a row of operating members engaged in the slots in the file selecting members, the operation of any of these file selecting members by their associated magnets will cause the lowermost edge of an operating member to be moved towards the lower left portion of the drawing thereby causing the active contacts, such as 23, associated with the operating member to engage corresponding passive contacts, such as 24, which in the preferred form illustrated take the form of bare wires.

The latching mechanism is shown at the lower right portion of Fig. 1. This mechanism comprises a rotatable shaft 25 having a plate 26 and a cam 27 secured thereto. A number of flat springs, such as 28, are riveted to the plate 26 at their uppermost ends. Each of these springs is positioned so as to normally clear the end of the file selecting member aligned therewith when the shaft 25 is rotated counter-clockwise. The shaft 25 is biassed in a clockwise direction by a flat spring 29 engaging an arm 30 which extends from the shaft. A further arm 31, Fig. 7, extending from the shaft engages a frame member to limit the clockwise rotation of the shaft. The spring 29 and arms 30 and 31 are shown in Figs. 7 and 8. A pawl 32 is pivotally secured to the end of the control member 14 and is biassed against the cam 27 by a coil spring 33. When the control member 14 is actuated by the operation of the control magnet 16, the pawl 32 drops into engagement with a tooth on cam 27 so that the subsequent restoration of the control member 14 causes the shaft 25 to rotate in a counter-clockwise direction. If at this time a file selecting member is actuated; the flat spring, such as 28, aligned therewith will engage a lug, such as

34, or 34' formed at the end thereof. The tension of the flat spring, such as 28, against the lug, such as 34, overcomes the opposing bias exerted on the file selecting member by the flat spring, such as 8, engaging the slot, such as 10, at the opposite end thereof; thereby holding the file selecting member actuated after the associated selecting magnet is released. When the control magnet 16 restores, the actuated rank selecting member is released causing all of the operating members associated therewith, excepting that held by the actuated file selecting member, to be raised out of engagement with their corresponding file selecting members.

The connection established as described above is released by the operation of the common release magnet 35 having an arm 36, biased by spring 12, extending from the armature thereof. The arm 36 raises the pawl 32 out of engagement with the tooth in the cam 27 to thereby permit restoration of the shaft 25 and the actuated file selecting member when magnet 35 is energized. When the actuated file selected member restores, the tension of the active contact springs, such as 23, which were operated pushes the operating member, such as 43, associated therewith up the inclined face of the arm, such as 21, of the rank selecting member into the normal position.

The sequence of operations described above in connection with the description of the mechanism may be more readily seen in Figs. 3 to 6, which illustrate various steps in the sequence of operations. All details not necessary to an understanding of the operations have been omitted from these figures to avoid confusion. In Fig. 3 the mechanism is shown at normal. In Fig. 4 the magnet armature 31 has been operated, thereby actuating the corresponding file selecting member 38 to the left, without effect at the moment, and depressing finger 15 into a position where 39 engages the arm 40 extending from rank selecting member 41 as the control member 14 is operated to the left by the subsequent energization of control magnet 16, thereby rotating the member 41 about its pivot point 42. The rotation of member 41 permits all of the operating members, such as 43 and 43', associated therewith to drop by gravity. Since file selecting member 38 is still actuated, the corresponding one of the operating members released by member 41 will rest on the member 38 until it restores and this operating member will then drop completely. It should be noted that pawl 32 has engaged the tooth in cam 27 preparatory to rotating shaft 25 clockwise when the control magnet 16 is subsequently released. In Fig. 5 magnet armature 31 has been released, thereby permitting file selecting member 38 associated therewith to restore. Finger 39 remains depressed since it is latched under the arm 40 of the rank selecting member 41 which is therefore held actuated. Magnet armature 44 was subsequently operated thereby actuating file selecting member 38', which in turn actuated the operating member 43' located at the intersection of selecting members 41 and 38', and thus operated the contact set associated with member 43'. The control magnet 16 is then released, as shown in Fig. 6, causing control member 14 to restore to the right. The restoration of member 14 rotated shaft 25 in a clockwise direction thus causing spring 28 to engage lug 34' formed at the end of member 38', thereby holding this member actuated after magnet armature 44 was subsequently released. All other springs corresponding to

spring 28 are in a position beyond the limit of travel of the file selecting members aligned therewith so that subsequent operations of these members are not interfered with and do not interfere with the latching mechanism. The restoration of the control member 14 also disengaged finger 39 from arm 40 thereby permitting selecting member 41 to be returned to normal by coil spring 49. Operating member 43' is frictionally held due to the tension of its associated active contact springs which press it against selecting member 38'. The displacement of operating member 43' to the left provides clearance between itself and the inclined arm of selecting member 41, upon which it normally rests, to thereby prevent interference with the restoration of the member 41. When the release magnet 35 is subsequently operated its armature raises the pawl 32 to disengage it from the tooth of cam 27, thus permitting the shaft 25 to rotate counter-clockwise to its normal position. Selecting member 38' consequently will be released and restores to the right. The pressure exerted on operating member 43' by its associated contact set now forces it up the inclined arm of member 41 to its normal resting position thereon as shown in Fig. 3.

As briefly mentioned heretofore, the switching mechanism is preferably constructed so as to extend connections directly to bare wire multiples, rather than to individual contacts, since it is particularly intended for use in telephone switching systems. In such an application the individual contacts of a number of corresponding switches would have to be connected together by strap wires. A considerable saving is effected when these individual contacts and associated wiring are eliminated. In order to use bare wire multiples to which circuits are directly extended, a number of identical switches are mounted one above the other with the bare wire multiples extending therebetween in parallel vertical planes. This form of construction has been illustrated in Figs. 6 to 10 which show the uppermost switch of a group. For convenience, there are ten vertical multiples each including 10 groups of conductors, each group comprising four conductors. Each switch includes one hundred active contact sets, each including four contacts, arranged in ten ranks of ten sets each. The forty conductors in each multiple are supported by insulating blocks, such as 48, shown in Figs. 2, 7, and 9. The insulating blocks of each multiple are secured to a panel, such as 22, at spaced intervals. As may be seen in Fig. 2, hook shaped flat contact springs, such as 23, are clamped at one end between the insulating blocks and clamping plates, such as 52, with the free ends of the springs aligned with corresponding ones of the multiple conductors, such as 24. As previously mentioned, the contact operating members are suspended on hooks which are formed in the clamping plates. The free ends of the contact springs, such as 23, are V-shaped so as to provide two points of contact when they engage the round multiple conductors. To each panel, such as 22, a number of assemblies each comprising a rank selecting member and a selecting magnet are attached adjacent a corresponding row of contact sets. The number of such assemblies included on a panel determines the number of switches in the whole unit. Each of the above assemblies includes two end plates, such as 53 and 54, Fig. 7, which are secured to the panels and which in turn support the selecting

magnets, the armatures therefor, and the rank selecting members. As may be seen in Fig. 9, one of the end plates of each pair is formed with extending arms, such as 11, 56, and 57, which serve as armature backstops, rank selecting member bearing supports, and rank selecting member stops, respectively. Ten such completed panels stand vertically, front to back, and are secured together by tie plates, such as 58 and 59. An end panel 60 is also secured to the tie plates. The end panel supports the control relay 16, guide plates slidably supporting the file selecting members, and the flat springs 9 for biasing these members. Similar guide plates, such as 61, are secured to the panel on the right as shown in Fig. 10. The latching mechanism for each switch is also secured to this latter panel. The release relay 35 is attached to an arm extending from tie plate 58, which also supports the contact sets, such as 8, associated with each selecting magnet. The control member 16 is slidably secured to the tie plate 58 by shoulder rivets, such as 62, as shown in Fig. 8. At the right of this figure there is shown a contact set 63 which is arranged to be closed, whenever the latching mechanism is operated, by the arm 39 extending from the latching mechanism shaft. These springs are used to open the circuit to the release magnet 35 after the latching mechanism is released thereby.

While the invention has been described with a certain degree of particularity, it should be understood that numerous modifications in the details of construction and arrangement of parts may be resorted to without departing from the true spirit and scope of the invention as defined in the subjoined claims.

What is claimed is:

1. In a switching mechanism, a plurality of contact sets disposed in ranks and files, a plurality of magnets each corresponding to a rank and to a file of said contact sets, a control magnet, means controlled by the operation of one of said magnets and said control magnet for selecting the corresponding rank of contact sets, and means responsive to a subsequent operation of any one of said magnets for selectively operating the contact set in the corresponding file and in the previously selected rank.

2. The combination in a cross-bar switch of a plurality of selecting magnets, a common magnet, a plurality of contact sets controlled by said magnets, and means responsive to the operation of one of said selecting magnets in conjunction with the operation of said common magnet followed by the release of said one selecting magnet and the operation of a second one of said selecting magnets for selectively operating one of said contact sets corresponding to said two selecting magnets.

3. In a switching mechanism, ranks and files of contact sets, a group of rank selecting members, a group of file selecting members, a group of magnets each corresponding to a rank selecting member and each associated with a file selecting member, a normally ineffective control member, fingers operated by said magnets rendering said control member effective to operate a corresponding rank selecting member, said operated rank selecting member being held by said control member independently of said magnets, operating members individual to said contact sets, said operated rank selecting member causing a corresponding rank of said operating members to be moved into operative relationship with

said file selecting members, whereby subsequent operations of said magnets are effective to selectively operate contact sets in the selected rank.

5. In a switching mechanism as claimed in claim 3, latching means operated in response to a subsequent operation of said control member to hold the file selecting member associated with the subsequently operated magnet independently thereof.

15 5. In a switching mechanism, a plurality of contact sets disposed in ranks and files, a plurality of selecting magnets each corresponding to a rank and to a file of said contact sets, a common magnet, means responsive to the joint operation of one of said selecting magnets and said common magnet for selecting the corresponding rank of said contact sets, and means responsive to a subsequent operation of one of said selecting magnets for selectively operating the contact set in the corresponding file and in the previously selected rank.

20 6. In a switching mechanism as claimed in claim 5, latching means operated in response to a subsequent operation of said common magnet for holding said operated contact set independently of said selecting magnets.

25 7. A switch comprising two intersecting groups of selecting members, a separately operable contact set at each point of intersection, magnets for operating said members, and means operated by said members in response to the sequential operation of certain of said magnets for selectively operating one of said contact sets and in response to a reversal in the order of operation of said 30 same certain magnets for selectively operating a different one of said contact sets.

35 8. In a switching mechanism, a plurality of contact sets disposed in ranks and files, a plurality of magnets each corresponding to a rank and to a file of said contact sets, a common magnet, and means responsive to the successive operation of one of said selecting magnets, said common magnet, and another one of said selecting magnets for selectively operating one of said 40 contact sets in accordance with the selecting magnets operated and the order of operation thereof.

45 9. In a switching mechanism, a first group of parallel bars, a second group of parallel bars intersecting said first group, a contact set at each point of intersection of said bars, individual contact operating members normally supported by the first group of bars, means operated to actuate any one of the bars in said first group to permit the contact operating members normally supported thereby to fall by gravity into engagement with said second group of bars, and means operated to actuate any one of the bars in said 50 second group to selectively operate the contact set at the intersection of said two actuated bars.

55 10. A switch comprising two intersecting groups of selecting members, a separately operable contact set at each point of intersection, a control magnet and a plurality of selecting 60 magnets for operating said members, and means operated by said members in response to the operation of a pair of said selecting magnets and said control magnet for selectively operating one of said contact sets in case one of said selecting magnets of said pair is operated before the other selecting magnet of said pair and for selectively operating another of said contact sets in case said other selecting magnet and said control magnet is operated before said one selecting 65 magnet.

11. In a cross-bar switch, two groups of crossed bars, individual magnets for operating each bar in one of said groups, a common magnet for operating any bar in the other of said groups, and means responsive to the operation of one of said individual magnets for selecting a corresponding one of the bars in said other group to be operated by said common magnet.

12. In a switching mechanism, a plurality of contact sets arranged in ranks and files, a pair of magnets each corresponding to one rank and one file of contact sets, means operated by said pair of magnets for operating a contact set in either of two ranks or in either of two files, the magnet of the pair first operated determining the rank of the contact set to be operated and the magnet subsequently operated determining the file of the contact set to be operated, and means for operating said pair of magnets sequentially in one order or in the reverse order whereby a contact set in either of two ranks and files may be operated dependent upon the order of operation of said pair of magnets.

13. A switch comprising a first group of selecting members and a second group of selecting members which intersect said first group members at a plurality of points of intersections, a separately operable contact set at each point of intersection, magnets for operating said members, each said magnet being individual to a first group member and individual to a second group member, means responsive to the operation of a first magnet for operating its individual first group member, means for thereafter operating the second group member individual to said operated first magnet, means responsive to the release of said first magnet for releasing its individual first group member, said first means responsive to the reoperation of said first magnet for reoperating its individual first group member, and means operated in response to the reoperation of said first group member for operating the contact set at the intersection point of said reoperated first group member and said operated second group member.

14. In a cross-bar switch, a first magnet, a second magnet, a first and a second bar individual to each magnet, said bars intersecting each other at four points of intersections, a separately operable contact set at each point of intersection, means responsive to a first operation, the release and then a reoperation of said first magnet for operating its individual first and second bars to operate the contact set at the intersection of said first and second bars individual to said first magnet, means responsive to a first operation,

the release and then a reoperation of said second magnet for operating its individual first and second bars to operate the contact set at the intersection of said first and second bars individual to said second magnet, means responsive to a first operation of said first magnet, the release of said first magnet and then the operation of said second magnet for operating said second bar individual to said first magnet and then said first bar individual to said second magnet to operate the contact set at the intersection of said second bar individual to said first magnet and said first bar individual to said first magnet, and means responsive to a first operation of said second magnet, the release of said second magnet and then the operation of said first magnet for operating said second bar individual to said second magnet and said first bar individual to said first magnet to operate the contact set at the intersection of said second bar individual to said second magnet and said first bar individual to said first magnet.

15. In a cross-bar switch, intersecting bars, a first magnet, a second magnet, a first, a second, a third and a fourth set of contacts, means responsive to a first operation, the release and then a reoperation of said first magnet for operating a first pair of said intersecting bars to operate said first set of contacts, means responsive to a first operation of said first magnet, the release of said first magnet and then the operation of said second magnet for operating a second pair of said intersecting bars to operate said second set of contacts, means responsive to a first operation of said first magnet, the release of said first magnet and then the operation of said third magnet for operating a third pair of said intersecting bars to operate said third set of contacts, and means responsive to a first operation of said second magnet, the release of said second magnet and then the operation of said fourth magnet for operating a fourth pair of said intersecting bars to operate said fourth set of contacts.
